UNITED STATES PATENT OFFICE.

CLEON BINE RUSH AND JAMES JOSEPH MORGAN, OF WELLINGTON, NEW ZEALAND.

TIPPING-GEAR FOR MOTOR-VEHICLES AND THE LIKE.

1,319,118.

Specification of Letters Patent.

Patented Oct. 21, 1919.

Application filed September 12, 1918. Serial No. 253,848.

To all whom it may concern:

Be it known that we, CLEON BINE RUSH and JAMES JOSEPH MORGAN, subjects of the King of Great Britain and Ireland, residing in Wellington, New Zealand, have invented a new and useful Improvement in Tipping-Gears for Motor-Vehicles and the like; and we do hereby declare the following to be a full, clear, and exact description of the same.

This invention relates to an improved tipping gear for motor vehicles and the like.

According hereto the body of the wagon is made to slide back upon "risers" or "summers" and when at the end of its slide to tip on a suitable check shaft. The check shaft is mounted in brackets attached to the body and is carried along to the tipping position in slots provided in the chassis 20 risers.

The means whereby the body is made to slide back comprise a winch with fast and loose drums which are so arranged that the body may be hauled back to the tipping 25 position by a winch rope or the like attached at one end to one of the drums, the said rope passing over a fixed pulley preferably situated on the back of the chassis, the other end of the rope being fixed to the body. 30 When the tipping is completed the body may be hauled back to the horizontal position by means of a rope fixed at one end to the body and at the other end to the second drum.

The check shaft above mentioned keeps 35 the body in the correct position, but if desired suitable guide plates or other guiding device may be mounted upon the "risers."

The sliding is facilitated by rollers suitably attached to the body which run upon 40 the "risers" above the chassis.

The winch is provided with a suitable clutch to enable the loose drum to be made fast. A pawl or the like device is provided to keep the apparatus locked. The apparatus 45 may be worked either by a hand lever as shown or by a mechanical drive from the engine.

One form of the invention is illustrated 50 in the accompanying drawings, in which similar numerals of reference indicate the same parts throughout.

Figure 1, is a side elevation showing the 55 position of the winch and ropes, and the various positions of the body while it is being tipped.

Fig. 2, shows a sectional view of a roller and of the check shaft.

Fig. 3, shows an elevation of Fig. 2.

Fig. 4, shows a plan of the winch.

Fig. 5, is an elevation of Fig. 4.

Fig. 6, illustrates a resilient form of attachment of the tipping chain to the body.

In the drawings, the body 1, is mounted on "risers" or "summers" 2, placed above the chassis 3. A plate 4, projects from the side 65 of the body over the uppermost of the "risers" 2, and upon the inside thereof. Such plate 4, receives a check shaft 5, provided with a suitable collar 6 as indicated in Figs. 2 and 3. The check shaft 5, runs in the slot 70 7, of the plate 8, and extends across to the opposite and corresponding "riser" which is similarly constructed. When the body is slid back this check-shaft rolls and thus prevents undue friction in the sliding process. 75 The check shaft 5, also tends to keep the body in the correct position, and it is upon this check shaft 5, that the body is tipped. The top of the chassis "riser" 2, is provided with a metal strip 9, upon which run the 80 rollers 10, mounted under the body "risers" 11, in a suitable manner.

The winch, as shown in Figs. 4 and 5 is suitably mounted in the position indicated in Fig. 1. Such winch consists of three 85 drums 12, 13 and 14, mounted on a common axle 15, which may be made to rotate by means of cranks 16, and a shaft 17, and gear wheels 18, and 19. The drum 14 is not keyed to the shaft 15, but may be attached 90 to it by a suitable clutch 20, operated by the crank 21. The rope 22, connects the drum 13, with the body at 23. The rope 24, connects the drum 14, with the body at 23, and is passed over a sheave 25, suitably 95 mounted at the rear of the chassis. The chain 26, connects the drum 12, with the body at 27, and is passed over the sheave 28, suitably placed at the rear of the chassis. The winch shaft 15, is provided with a 100 ratchet wheel 29, with which a pawl 30, may be made to engage.

The attachment of the tipping chain 26, to the body at 27, is preferably made resilient, and one form of attachment is shown in 105 Fig. 6.

The operation of the device is as follows:

When the body 1, is in its normal position, as shown in full lines in Fig. 1, the chain 26, is slack, the clutch 20, is engaged with 110

the drum 14, the rope 22, on the fast drum 13, is fully wound and the rope 24, on the loose drum 14, is paid out (*i. e.* spent). In commencing the sliding operation preparatory to tipping, the pawl 30, is released. The clutch is engaged and the winch is set in operation in such a way as to cause the rope 24, to wind up on to the drum 14, whereby at the same time the rope 22, is unwound. 10 Consequently the point 23, (*i. e.* the point of attachment of these ropes to the body), and thereby the body itself, move toward the tipping position as shown in dotted lines 31, Fig. 1. The clutch is now disengaged 15 whereby the rope 24, on the loose drum 14, is released and the tipping is completed by continuing to work the winch in the same manner as before, whereby the chain 26, will be wound up thereby insuring the completion 20 of the tipping, as shown in dotted lines 32, irrespective of the distribution of the load in the body.

To return the body to its normal position, the winch is wound in the reverse direction 25 whereby the rope is wound on to the fast drum 13 and the chain paid out, the clutch being disengaged during this process.

When the winding is completed and the body is returned to the ordinary horizontal 30 position, as shown in full lines in Fig. 1, the

clutch 20 is put in and the pawl 30 is brought into engagement with the ratchet wheel 29 and the apparatus is thereby locked.

What we claim is:—

In a tipping wagon, a body adapted to slide, a rope winch whereby the body may be made to slide to tipping position and be recovered therefrom, rollers on said body, "risers" on which said rollers are adapted to roll, said risers being formed with substantially horizontal slots, plates secured to the body and adjacent said "risers", a check shaft mounted in said plates and fitting in said slots, said winch comprising three drums, one of said drums loose on its shaft, 45 a clutch to lock said loose drum to its shaft, and a flexible member attached to each of said drums, one of which members is adapted to tilt said body, the other members adapted to impart forward and rearward motion to 50 said body.

In testimony whereof, we have signed our names to this specification in the presence of two subscribing witnesses.

CLEON BINE RUSH.
JAMES JOSEPH MORGAN.
